SHOCK RESISTANCE DEMONSTRATOR

Herbert D. Hooker, Poplar Bluff, Mo.

Application December 8, 1949, Serial No. 131,763

9 Claims. (Cl. 35—49)

1

My invention consists in new and useful improvements in apparatus for demonstrating the shock and water resistant properties of watches and similar articles of manufacture. An object of the invention is to provide a device of this character which will automatically subject a watch or other article to repeated impacts against an abutment or back stop and immersion in a water-filled container, intermittently withdrawing the watch from the container and returning it to its initial position.

A further object of my invention is to construct such a demonstrating apparatus as above referred to, as a self-contained unit, in a form which is attractive to the eye and readily adaptable for advertising purposes such for example, as window and counter displays in jewelry stores, commanding the attention of prospective customers and visually demonstrating in a most convincing manner, the resistant qualities of the advertised product.

A still further object of the invention resides in the embodiment of an improved catapult mechanism which is preferably actuated by an electric motor or other suitable continuously operated prime motor, properly geared for speed reduction and equipped with an automatic clutch device which first causes the catapult to be retracted against a suitable spring resistance and then released for forcefully projecting the watch against an abutment, followed by an immersion in a water-filled container and then returned to its original position, repeating this sequence as long as the motive power is in operation.

With the above and other objects in view which will appear as the description proceeds, my invention consists in the novel features herein set forth, illustrated in the accompanying drawings and more particularly pointed out in the appended claims.

Referring to the drawings in which numerals of like character designate similar parts throughout the several views:

Figure 1 is a perspective view of the self-contained unit showing the catapult arm in the course of being retracted;

Figure 2 is a longitudinal, vertical, sectional view through the device, showing the clutch releasing mechanism in clutch releasing position;

Figure 3 is a fragmentary top plan view of the casing with the top removed to illustrate working parts;

Figure 4 is a sectional view taken on line 4—4 of Figure 3;

Figure 5 is a fragmentary sectional view of the

2

mechanism shown in Figure 2, but showing the clutch releasing mechanism in inactive position;

Figure 6 is a sectional view taken on line 6—6 of Figure 2 with the clutch released; and

Figure 7 is a similar sectional view taken on line 7—7 of Figure 5 showing the clutch in engagement.

In the drawing 8 generally represents the housing or container for my improved demonstrating apparatus and consists of a base 9, side walls 10, a front wall 11, a rear wall 12 and a hinged top 13, forming a casing for the operating mechanism. The base 9 is extended forwardly beyond the front wall 11 as at 14, to form a support for a water receptacle 15, the side walls 10 being also extended and cut away as at 16 and joined by a low supplemental front wall 17 which completes the supporting platform or compartment for the water receptacle 15.

At a suitable point on the hinged top 13 I provide a horizontally disposed catapult arm 18, pivotally mounted at one end on a pin or bolt 19 which extends through the top 13 and may be held in place by the nut 20. The free end of the catapult arm 18 carries an article receiving seat 21 having a semi-circular vertical rear wall 22 and being opened at its forward end where it terminates in a forwardly and downwardly inclined mouth 23. By means of a coil spring or other tension device 24, the catapult arm is normally urged in a forward direction, said spring being attached to the front wall 11 by means of a hook or the like 25 and similarly secured at 26 to the catapult arm.

As will be seen from Figure 2, the rear wall 22 of the article seat 21 is provided with a horizontal opening 27 through which a length of flexible cord or line 28 is adapted to slide, the outer end of said cord being attached by any suitable means to the watch 29 being demonstrated.

The opposite end of the line 28 is adapted to be reeled upon a drum which is intermittently released by mechanism hereinafter described, so that the watch and catapult arm are alternately retracted against the tension of the spring 24, and projected forcefully to eject the watch therefrom.

The mechanism for operating and controlling the sequence of operation is enclosed in the casing previously described and comprises an electric motor 30 which, through a system of gear reduction, drives a main gear 31, fixed on a transverse shaft 32, supported at one end in a vertical support 33 with its opposite end extending through two spaced vertical supports 34 and

35 which, together with a third vertical support 36 form the supporting structure for the clutch and drum controlling mechanism.

On the shaft 32 and located between the upright supports 34 and 35, is a spur gear 37 which meshes with a larger gear 38, keyed to a parallel shaft 39 which is rotatably supported in the upright partitions 34, 35 and 36. Also keyed to the shaft 39 and constantly rotating therewith, is a clutch plate 40 in the form of a flanged disk, the inner face of which is provided with a pair of clutch pins 41 adapted to operatively engage complementary recesses 42 in a drum 43 freely rotatable upon the shaft 39, as will be seen from Figures 6 and 7. A coil spring 44, interposed between the drum 43 and a gear 45, normally urges the drum 43 into engagement with adjacent face of the clutch disk 40.

The gear 45 is keyed to the shaft 39 and operatively engages a companion gear 46, mounted on shaft 47 which is supported between the uprights 35 and 36, said last named gear being provided with a hub 48, carrying a radially projecting arm 49 which constantly rotates with the gear 46 as will be seen from Figures 2 and 5. Adjacent the gear 46 I provide a clutch controlling arm 50, keyed to a shaft 51 and having at its free end an abutment 52 arranged in line for intermittent engagement by the arm 49 for the purpose hereinafter set forth.

The clutch controlling mechanism comprises a second arm 53 also keyed to the shaft 51 and having a rearward projection 54 at its upper extremity, to which is secured one end of a spring 55, the opposite end of which is secured by means of a hook 56 to the inner face of the front wall 11. Thus, there is a constant tendency for the arm 53 with the arm 50, to be rocked counterclockwise on the shaft 51, to bring the abutment 52 into line for engagement by the rotating arm 49.

The upper end of the arm 53 is connected at 57 to a clutch controlling yoke 58 which as will be seen from Figures 2 and 5, comprises a pair of vertically spaced, parallel rails 59 joined at their extremities by substantially semi-circular portions 60. Turning to Figures 3 and 6, it will be seen that the rails 59 are interposed between the adjacent faces of the drum 43 and the clutch plate 45, preferably embracing the periphery of the clutch disk, in sliding engagement with its flange. Each of the rails 59 is provided with an inclined face or wedge portion, adjacent the face of the drum 43, as shown at 61 in Figure 3, said wedge portions gradually becoming wider in a direction away from the connecting point 57, so that when the yoke 58 is drawn to the left in Figures 2 and 3, the widest portions of the wedges 61 enter the space between the clutch disk 40 and drum 43 to force the drum away from the clutch disk and permit its free counterclockwise rotation on the shaft 47. Movement of the yoke 58 to the right displaces the wedges 61 and permits engagement of the clutch pins 41 with the recesses 42 in the drum 43, by the action of the coil spring 44. As before stated, the yoke 58 is connected at 57 to the arm 53 and therefore, counterclockwise rocking of the arm 53 through the action of the rotating arm 49 and its co-operating arm 50, causes the longitudinal displacement of the wedges 61 of the yoke, to permit clutch engagement, and the reverse action for disengaging the clutch, is effected by the coil spring 55 which normally tends to rock the arms 53 and 50 in a counterclockwise direction.

In order to control the operation of the yoke and clutch and cause the intermittent projection and return of the catapult arm 18, I provide a latch arm 62 pivotally mounted intermediate its ends on a cross rod 63. One end of the arm 62 is connected to a tension spring 64 fixed to a hook 65 at its lower end, on the base 9 while the opposite end of said arm 62 forms the actual latch and tripping abutment. As will be seen from Figures 2 and 5, the upper edge of the arm 62 at its latch end is cut away to form a downwardly inclined track 66 which terminates in a deep notch 67, adapted to be engaged by a transversely projecting lug 68 fixed on the arm 53. Thus, the clockwise rocking of the arm 53, causes the lug 68 to ride along the track 66 until it enters the notch 67 whereupon the arm 53 and the yoke 58 are locked in their extreme right hand position to maintain the clutch in engagement and cause rotation of the drum 43.

As before stated, the flexible line 28, connected to the article 29 being demonstrated, is reeled upon the drum 43. The line 28 preferably runs from the article receiving seat 21 over a pulley 69 mounted on the top 13 of the casing and then through an opening 70 in the top where it is connected by any suitable means to the periphery of the drum 43. Thus, as the drum 43 rotates in clockwise direction, the line is reeled thereon and by contact of article 29 with the rear wall 22 of the seat 21, the catapult arm 18 is retracted against the tension of spring 24.

In order to release the clutch and permit the projection of the article being demonstrated, I provide a trip element 71 which consists of an upwardly directed member integral with the arm 62 which projects through an opening 72 in the top 13, in the line for engagement by the article receiving seat 21, when it reaches its extreme retracted position as shown in Figure 5. This engagement of seat 21 with the tripping element 71 depresses the latch end of arm 62 and releases the lug 68 from the notch 67, whereupon the spring 55 causes longitudinal movement of the yoke 58 toward the left to interpose the wedges 61 between the clutch plate 40 and the drum 43, thereby permitting freedom of rotation of the drum in a counterclockwise direction. Upon thus releasing the clutch the spring 24 is permitted to forcefully swing the catapult arm 18 on its pivot 19 and unreel the line 28 from the drum 43.

To effectively eject the article 29 from its seat 21, it is necessary to provide for an abrupt stoppage of the forward action of the catapult arm 18. This may be accomplished by simply providing an upwardly directed stop at the forward end of the top 13 in line with the movement of the catapult arm 18. However, I have found that a somewhat more exaggerated and vivid effect may be accomplished by a novel structure which operatively connects the catapult stop with the abutment or back stop against which the article is to receive impact. This arrangement will best be seen from Figure 2 wherein 73 represents a vertically extending abutment or back stop, preferably in the form of a sheet of lucite or other plastic material, supported by a pair of vertical arms 74 which are loosely secured as at 75 in a transverse slot in the end of the base projection 14. The lower extremities of the arms 74 are fastened to a connecting rod 76, the rear end of which is pivotally connected at 77 to an upwardly extending stop arm 78. The stop arm 78 is pivoted intermediate its ends to a support 79 fixed to the inner face of the front wall 11 and its

upper end 80 projects through an opening 81 in the top 13 in line for engagement by the catapult arm 18. Thus, when the catapult arm contacts the projecting end or stop 80, it abruptly stops and ejects the article 29 toward the impact abutment 73. Naturally, a forceful impact of article 29 against abutment 73 results, but a more exaggerated effect is obtained because of the fact that the forward movement of the upwardly projecting end 80 causes the arm 78 to rock on its support 79 and through the connecting rod 76 the abutment 73 is given a slight lateral movement, simultaneously with the impact of article 29.

Preferably, the line 28 is of sufficient length and the weight of the drum predetermined, to permit a slight overrun of the drum in its counterclockwise rotation. Thus, when the article 29 is ejected from the seat 21 and before it has descended into the water container 15, the overrunning of the drum causes the line 28 to be reeled for a portion of its length in the opposite direction, by the momentum of the drum. Then, when the drum starts its reverse or clockwise rotation, the article on the end of line 28 is first caused to descend into the water in receptacle 15 until the end of the line attached to the drum 43, starts to reel in its normal direction on the drum, whereupon the article is elevated from the receptacle 15 and drawn into the seat 21 on the catapult arm.

In order to facilitate the withdrawal of the article from the receptacle 15, I preferably provide an apron 82 which may be composed of any suitable material such as plastic, and is secured to the front wall 11 overlying the inner edge of the container 15.

The sequence of operation of my improved demonstrating apparatus is as follows:

An article such as a watch 29 is secured to the end of the line 28 and the motor 30 is set into operation which causes a continuous rotation of the main gear 31 and therewith, the shaft 32 and the spur gear 37. From the gear 37, gear 38, shaft 39 and gear 44 are caused to constantly rotate and therewith, the clutch plate 40, the drum 43 being in the position shown in Figure 7, in engagement with the clutch plate 40 and the clutch controlling yoke 46 in its extreme rightward position shown in Figure 5. The drum is rotated in clockwise direction to reel the line 28 thereon until the article receiving seat 21 abuts the tripping element 71, to release the latch 87—88. Thereupon, the yoke 58 is caused to move to the left under the tension of spring 55, bringing the widest portion of the wedges 61 of the rails 59, into wedging engagement between the drum and clutch plate, to force the drum out of engagement and permit freedom of rotation in a counterclockwise direction. The tension of the spring 24 causes the rapid forward movement of the catapult arm 18 until it engages the upward projection 80, when the article is forcefully ejected from the seat 21 and strikes the vertical abutment 73. The article is then caused to descend into the container 15 by means of the overrun above described, the rotating arm 49 having engaged the abutment 52 on arm 50, to return the yoke 58 to its inoperative position with the resultant engagement of the clutch and drum to rotate the latter in clockwise direction. The article 29 on the line 28 is then drawn upwardly over the apron 82 until it again enters the seat 21 on the catapult arm 18, the continued reeling of the line causing the return of the catapult arm

13 to its retracted position, when the above described sequence is repeated.

From the foregoing, it is believed that my invention may be readily understood by those skilled in the art, without further description, it being borne in mind that numerous changes may be made in the details of construction without departing from the spirit of the invention as set forth in the appended claims.

I claim:

1. Apparatus for demonstrating the shock resistant properties of watches and similar articles, comprising a support, a back stop adjacent one end thereof, a catapult mounted on said support and carrying an article receptacle, means for alternately retracting and projecting said catapult and receptacle in line with said back stop, whereby an article in said receptacle is projected against said back stop, and means for automatically returning the projected article to said receptacle.

2. Apparatus for demonstrating the shock and water resistant properties of watches and similar articles, comprising a support, a back stop adjacent one end thereof, a water container below said back stop, a catapult arm pivotally mounted at one end, on said support and carrying at its free end an article receptacle, means for alternately retracting and projecting said arm and receptacle through an arc in line with said back stop, whereby an article in said receptacle is projected against said back stop and immersed in said water container, and means for automatically recovering said article from said container and returning to said receptacle.

3. Apparatus for demonstrating the shock resistant properties of watches and similar articles, including an article projecting unit, comprising a pivotally mounted catapult arm movable in an arc between retracted and projected positions and having an article receptacle at its free end, resilient means for swinging said arm from retracted position, an abutment for intercepting said movement and causing the ejection of an article in said receptacle, a back stop spaced from said unit and lying in the path of movement of an ejected article, a flexible line slidably engaging said receptacle and secured at one end to said article, a power driven shaft, a drum freely rotatable on said shaft for reeling the opposite end of said line to retract said article and with it said arm and receptacle, against the tension of said resilient means, a clutch for operatively connecting said shaft and drum, means actuated by said shaft for locking said clutch in operative position, to reel said line on said drum, and trip mechanism actuated by said arm upon reaching retracted position, for releasing said clutch to permit free reverse rotation of said drum for unreeling said line under the force of said resilient means, whereby said article is projected from said receptacle against said back stop.

4. Apparatus as claimed in claim 3 wherein said back stop is tiltably mounted, said abutment being mounted for limited pivotal movement in the direction of the back stop, and means connecting said abutment and back stop to transmit movement of the former to the latter.

5. In apparatus for demonstrating the shock resistant properties of watches and similar articles, including a catapult arm pivoted for swinging movement between two points and car-

rying an article receptacle at its free end, tension means for swinging said arm toward one of said points to forcefully eject an article from said receptacle, and a back stop lying in the path of movement of said ejected article; article controlling mechanism comprising a continually rotating, power driven shaft, a drum freely rotatable and axially displaceable thereon, a flexible line slidably engaging said receptacle and connected at one end to an article therein, its other end being connected to said drum for reeling thereon, a clutch disk fixed on said shaft, resilient means normally urging said drum into engagement with said clutch disk for rotation therewith, a clutch releasing member interposed between said clutch disk and drum to free the latter on the shaft, means actuated by said power driven shaft for intermittently shifting said clutch releasing member to inoperative position to permit engagement of the clutch and drum, a latch for locking said releasing member in operative position, whereby said line is reeled on the drum, retracting the catapult arm through engagement of the article with said article receptacle, and a trip device actuated by the retraction of said arm for tripping said latch to permit the return of said clutch releasing member to inoperative position to free said drum for unreeling said line under the force of said tension means, whereby said article is projected from the receptacle, against said back stop.

6. Apparatus as claimed in claim 5 wherein said clutch releasing member comprises a transversely slidable yoke having at least one wedge surface which normally displaces said drum on said shaft to release the clutch.

7. Apparatus for demonstrating the shock resistant properties of watches or similar articles, comprising a base, a vertical back stop at one end of said base, a housing on said base, spaced from said back stop, a catapult arm pivotally mounted at one end, on the top of said housing for reciprocating movement in a horizontal plane, an article receptacle carried at the free end of said arm, a catapult spring for projecting said arm in the direction of said back stop, a line of flexible material, means connecting one end thereof to the free end of said arm, a freely rotatable drum slidably mounted on said shaft in said housing means for securing the opposite end of said line to the periphery of said drum for reeling thereon, to retract the arm against the tension of said catapult spring, a clutch plate on said shaft and rotatable therewith, spring means normally urging said drum toward said clutch plate for operative engagement therewith, a clutch releasing element, means normally urging

said element into position between said plate and drum to free the latter on the shaft, means driven by said shaft for intermittently withdrawing said releasing element to permit engagement of said plate and drum, a latch for maintaining said element in withdrawn position, and means actuated by said catapult arm when the latter reaches retracted position, to release said latch.

10 8. Apparatus for demonstrating the shock resistant properties of watches and similar articles, a comprising a base, a catapult arm pivotally mounted at one end on said base for swinging movement in a horizontal plane, an article receptacle carried at the free end of said arm and having an aperture in the rear wall thereof, a line of flexible material slidable through said aperture and adapted to be secured at one end, to an article resting in said receptacle, spring means normally urging said arm in one direction, a power driven shaft, a drum freely rotatable on said shaft and having means for securing the opposite end of said line, clutch means normally urged into operative position for connecting said shaft and drum for reeling said line, to retract said arm in the opposite direction against the tension of said spring means, through engagement of said article with the wall of said receptacle, and means operable upon the retraction of said arm for intermittently releasing said clutch to free said drum, whereby said line may be unreeled and the article projected from said receptacle against said back stop.

9. Apparatus for demonstrating the shock resistant properties of watches and similar articles, comprising a support, a back stop at one end thereof, a catapult on said support and carrying an article receptacle, resilient means normally urging said catapult toward said abutment, a 40 drum rotatably mounted on said support, a flexible line fixed at one end to said drum and adapted to be reeled thereon, the other end of said line passing freely through an opening in the rear of said receptacle and being fixed to an article to be demonstrated, a prime mover, a clutch for operatively connecting said prime mover and drum to reel the line on the latter, drawing said article into said receptacle, the continued reeling of said line causing said receptacle and catapult to be retracted, and a latch member operable by contact of said catapult to disengage said clutch and to release the catapult under the force of said resilient means, whereby an article in said receptacle is projected against 50 said back stop.
